CLAIM

The ornamental design for an industrial robot, as shown and described.

DESCRIPTION

1. Industrial robot

1.1 : Front

1.2 : Back

1.3 : Left

1.4 : Right

1.5 : Top

1.6 : Bottom

1.7 : Perspective

Reproduction 1.1 is a front view of an Industrial robot, showing our new design; reproduction 1.2 is a back view thereof; reproduction 1.3 is a left view thereof; reproduction 1.4 is a right view thereof; reproduction 1.5 is a top view

(Continued)

thereof; reproduction 1.6 is a bottom view thereof; and reproduction 1.7 is a perspective view thereof.
